TREATMENT OF HYDROCARBON OILS

Jacque C. Morrell and Gustav Egloff, Chicago,
Ill., assignors, by mesne assignments, to Uni-
versal Oil Products Company, Chicago, Ill., a
corporation of Delaware

No Drawing. Application June 19, 1931, Serial
No. 545,476. Renewed July 1, 1935

5 Claims. (Cl. 196—36)

This invention relates to the treatment of hydrocarbon oils, and refers more particularly to the refining of relatively low boiling hydrocarbon distillates at elevated temperatures, especially those resulting from the conversion of relatively high boiling hydrocarbons at elevated temperatures.

More specifically, the invention comprises subjecting hydrocarbon oil vapors to treatment with hydrochloric acid and solutions of copper salts in the presence of solid contact materials containing solid salts of copper or other metals, the solid salts employed being preferably either substantially insoluble or of definitely limited solubility, oxygen-containing gases and/or steam being admixed with the oil vapors when desired. The hydrochloric acid may be added as a gas or as an aqueous solution of any desired strength either separately or in solution with the copper salt or salts thus employed.

As examples of salts of copper which may be employed in solution according to the process of the invention may be mentioned cupric sulfate, cupric chloride, cupric nitrate, cupric chlorate, cupric bromate, cupric chromate, etcetera, these salts being uniformly characterized by a high solubility in water. The solubility of the less soluble salts is influenced by the presence of hydrochloric acid generally in the direction of increased solubility, and sometimes with the formation of double salts which exert refining effect according to the particular acid radicals that are present.

As examples of salts of metals which may be used as solids may be mentioned such salts as, for example, the chlorides and bromides of copper and mercury, the compounds corresponding to the lower valence in these metals being practically insoluble in water or dilute hydrochloric acid solution. Among other relatively insoluble salts may be mentioned certain phosphates, for example, those of zinc, tin, nickel, cobalt, copper, mercury, calcium, barium, strontium, etcetera. In regard to the use of more soluble salts, conditions of operation may be so maintained that there is present at all times a solid phase of a metallic salt in equilibrium with the salt solution which is employed.

As examples of oxygen-containing gases air, oxygen, ozone, etcetera, alone or in combination may be mentioned, ozonized air having been found to be particularly efficacious in some instances.

In some cases it may be found preferable to space the finely divided solid salts by supporting

them on or mixing them with relatively inert materials of a non-metallic nature such as fuller's earth, clays, bentonite, bauxite, crushed firebrick, pumice stone, etcetera, this expedient serving to expose more surface and prevent the 5 agglomeration of the salts into masses too large for effective action. The function of the salts or mixtures thereof employed may be of a true chemical nature or they may function merely as catalysts.

The usual method of refining cracked distillates is to subject them to treatment with sulfuric acid and alkaline solutions, including plumbite solutions consisting of litharge dissolved in alkaline solutions in various combinations of treatment and subsequently to subject the acid treated product to redistillation usually in the presence of steam. The present invention permits the direct treatment of the hydrocarbon vapors from the cracking process, reducing the 20 cost of reagents and eliminating the redistillation or rerunning operation, although it is within the scope of the invention to revaporize the product in a subsequent operation and subject the vapors to treatment as described.

The invention is more particularly directed to the treatment of vapors of lower boiling cracked distillates though straight run distillates may also be treated within the scope of the invention.

In applying the process of the invention to practice any suitable equipment may be employed which will permit contacting a mixture of hydrocarbon vapors, oxygen-containing gases and/or steam with hydrochloric acid, copper salt solutions and solid metallic salts, for example, a suitable tower or chamber packed with a selected mixture of solid contact materials may be employed following the fractionator of a cracking system, the liquid and/or gaseous 35 treating reagents being introduced at suitable points along the line of flow of the ascending or descending vapors, thus permitting proper contact with the solid materials. Similarly, any device which permits the efficient contacting of the hydrocarbon vapors undergoing treatment with liquids, gases and solids may be employed. The solid contacting materials may sometimes be employed in successive strata of varying composition, or masses of uniform or varying composition 40 may be supported in a tower on superimposed plates designed to effect intimate contact.

A convenient method of operation consists in introducing the hydrocarbon vapors to be treated 55

into a point near the bottom of a tower containing contact material supported upon a perforated plate, hydrochloric acid being added as a solution or as gas at the same point. Minor amounts of air may also be added to the vapor and steam or water necessary to maintain the copper salt solutions at proper concentrations and prevent crystallization. The particular copper salt solution to be employed which may be 5 commonly a saturated aqueous solution, may be introduced above the solid contact mass and caused to flow downwardly by gravity counter-current to the ascending mixture of hydrocarbon oil vapors and hydrochloric acid. In this 10 type of equipment it may be found that treating and fractionation are effected in one step so that subsequent rectification of vapors is not necessary.

It has been found desirable to neutralize the 20 vapors before or after condensation and to this end the vapors may be treated with ammonia gas or pass counterflow to solutions of alkalis in auxiliary neutralizing equipment, or the condensed vapors may be treated with liquid alkalis 25 such as solutions of caustic soda, ammonia, or the like, the traces of reagents and reaction products remaining being washed out with water when found necessary.

The reactions involved in treatments conducted 30 within the scope of the invention have been observed to produce effects comparable with those produced by sulfuric acid of varying strength used after the customary methods of treatment. The amounts of hydrochloric acid 35 used will vary with the character of the vapors treated from a fraction of a percent to as high as 5% by weight of the oil vapors treated in cases where relatively heavy treatments are desired, the amount of copper salt solution used 40 varying with the type of salt dissolved and the concentration of the solution employed and other factors. The amounts of oxidizing gas and steam used with the hydrochloric acid may also be varied to produce a wide variety of treating 45 effects.

The effects produced upon oil vapors, particularly those produced from the cracking of heavy hydrocarbon oils by the use of oxidizing gases and copper salts characteristic of the invention are in general those of polymerization or condensation of relatively highly unsaturated hydrocarbons or their derivatives, along with some effect on certain sulfur derivatives either to "sweeten" or eliminate them. The net result 50 is the controllable elimination of groups of compounds which are readily polymerized under oxidizing conditions to form substances of a gummy or resinous nature which are undesirable in motor fuel, and a substantial reduction 55 in sulfur content.

Various temperatures of treatment may be employed, for example, from 275-600° F., more or less, and the pressure may be subatmospheric, atmospheric or superatmospheric. While the results 60 may vary with the conditions employed, the pressures and temperatures are chosen so that the hydrocarbons are treated substantially in the vapor phase.

As examples of the operation of the process of 70 the invention and of the results obtained, a California cracked distillate of approximately motor fuel boiling range may be vaporized and subjected to treatment with a mixture of hydrochloric acid, oxygen and steam during the 75 passage of the vapors in an upward direction

through a stationary contact mass consisting of a mixture of a finely divided cuprous chloride supported on fuller's earth, (the weight of the earth being approximately four times that of the salt) counterflow to a descending solution of 5 cupric chloride. The hydrochloric acid may be introduced either as a moderately dilute aqueous solution or as a gas in an amount equivalent to approximately four pounds per barrel with air sufficient to provide the oxygen theoretically required to combine with the hydrogen in the hydrochloric acid. Steam is used at the rate of approximately two pounds per barrel. The untreated product may show a gum content of approximately 525 mgs. per 100 ccs. and have a 10 reddish brown color, with a sulfur content of approximately 0.35%. The treated product after suitable separation from spent reagents, neutralizing with alkalis and washing with water, may show a gum content of approximately 10 20 mgs. and a color of plus 30 on the Saybolt scale. The sulfur content may be found to be as low as 0.15%.

In the case of a mixed Mid-Continent and West Texas cracked distillate treated in the 25 same manner with approximately the same amount of hydrochloric acid and cupric chloride solution, using mercurous chloride in place of cuprous chloride, the gum content may be reduced from 350 mgs. to 15 and the color raised 30 from a light amber to approximately 30 on the Saybolt scale. The sulfur content may be reduced from 0.4% to approximately 0.22%.

The process of the invention is particularly suitable to the treatment of cracked distillates 35 produced from California oils. In some cases the untreated distillates may contain 600 mgs. of gum and have a dark reddish color while the treated distillates may have a gum content of less than 40 mgs. and a color of 25 to 30 on 40 the Saybolt scale. The sulfur content may be reduced from 0.5% to 0.20%.

The foregoing description and examples have disclosed a process applicable to the treatment 45 of hydrocarbon oil vapors which has a wide applicability and is capable of great variations in the methods of operation and the amounts of reagents employed. Therefore, the specific cases cited are not to be construed in a limiting sense upon the broad scope of the invention as many 50 other modifications can be used and examples of results therefrom given.

We claim as our invention:

1. A process for refining hydrocarbon vapors which comprises treating the same with added 55 aqueous hydrogen chloride in the presence of a relatively stable water soluble copper salt in aqueous solution and a relatively stable copper salt in amount above that which will dissolve in the aqueous hydrogen chloride and the aqueous solution whereby to maintain a solid phase 60 of the last named salt.

2. A process for refining hydrocarbon vapors which comprises treating the same with added aqueous hydrogen chloride in the presence of 65 solid cuprous chloride and an aqueous solution of cupric chloride.

3. A process for refining cracked hydrocarbon distillates which comprises treating the distillate at a temperature between 275° F. and 600° F. 70 with added aqueous hydrogen chloride in the presence of copper salt in aqueous solution and in solid form.

4. A process for refining cracked hydrocarbon distillates which comprises treating the distillate 75

at a temperature between 275° F. and 600° F. with added aqueous hydrogen chloride and an aqueous solution of a water soluble copper salt in the presence of a solid copper salt which is substantially insoluble in the aqueous hydrogen chloride and said aqueous solution.

5. A process for refining cracked hydrocarbon

distillates which comprises treating the distillate at a temperature between 275° F. and 600° F. with added aqueous hydrogen chloride and a water solution of cupric chloride in the presence of solid cuprous chloride.
